Attorney

UNITED STATES PATENT OFFICE.

HARRY H. KONERMAN, OF NEWPORT, KENTUCKY, ASSIGNOR TO THE GLOBE REGISTER COMPANY, OF CINCINNATI, OHIO, A CORPORATION OF OHIO.

AUTOGRAPHIC REGISTER.

Application filed August 3, 1922. Serial No. 579,374.

To all whom it may concern:

Be it known that I, HARRY H. KONERMAN, a citizen of the United States of America, and a resident of Newport, in the county of 5 Campbell and State of Kentucky, have invented a new and useful Improvement in Autographic Registers, of which the following is a specification.

An object of my invention is to provide 10 a simple and efficient conditioning device to be employed with autographic registers, whereby the several sheets of paper employed therein may be automatically stopped after having been moved a determinable 15 distance.

Another object of my invention is to provide a device having a minimum of moving parts.

Another object of my invention is to provide 20 a device, the parts of which are subject to very slight wear, thereby prolonging the life and efficient operation of the device.

These and other objects are attained by 25 the means described herein and disclosed in the accompanying drawings, in which:—

Fig. 1, is a perspective view of a register embodying my invention.

Fig. 2, is a sectional view taken on line 2—2 of Fig. 3.

Fig. 3, is a sectional view taken on line 30 3—3 of Fig. 2.

The register 4 comprises the ordinary casing 5, within which are contained rolls 8, comprising several sheets which may be 35 fed to and below an opening or aperture 6 in the top plate 7 of the casing. The rolls of paper have disposed between them suitable sheets of copying or carbon paper, as is common in the art. The sheets of paper 40 are fed thru the device by means of rollers 9, 10 and 11, mounted on a shaft 12, cooperating with rollers 13, 14 and 15, mounted on a shaft 16. The shaft 12 is revolvably mounted upon the sides of the casing 4, and 45 carries a gear 17, in engagement with a gear 18 carried by the shaft 16, which shaft 16 has one of its ends revolvably mounted upon one side of the casing, and has its other end supported by a bracket 19, carried by a cross bar 20 extending between the sides of the register. The rollers 9, 10, are spaced from the rollers 13 and 15, at a distance slightly less than the thickness of the 50 several sheets 21, fed below the aperture 6 in the top plate. The sheets are provided

with registering slots 22, which slots are in alignment with the rollers 13 and 15, and which on registering with said rollers 13 and 15, preclude further movement of the sheets by means of the rollers. 60

The feed roller 11 has an enlarged axial bore 23, thru which the shaft 12 extends. This enlarged bore permits the roller 11 to assume a lowermost position such that the roller 11 will exert no appreciable pressure 65 upon the several sheets 21, and upon the roller 14 in substantial vertical alignment with the roller 11. The roller 11 is adapted to revolve with the shaft 12, this being accomplished by means of a pair of pins 24 70 and 25, carried by the roller, and a pin 26 carried by the enlarged portion 27 of the shaft 12, the pin 26 being disposed between the pins 24 and 25. The portion 27 and collar 28 serve to space the roller 11 from 75 rollers 9 and 10 which are fixed upon the shaft.

A shaft 29 mounted between the sides of the register, carries a lever 30, one end of which extends thru an elongated slot 31, 80 formed in one wall of the register, and carrying upon its end a suitable finger or thumb piece 32. Whereby said lever may be employed to revolvably actuate the shaft 29. The shaft 29 carries a bracket 33 revolvably 85 supporting a mutilated wheel or feed roller 34. The wheel 34 is weighted on that side which is mutilated, wherefore the wheel tends at all times to assume a position such that the mutilated portion thereof will be 90 lowermost. The mutilation in feed or roller wheel 34 comprises an arcuate notch 35, into which the feed roller 11 may extend. A spring 36, yieldingly resists movement of the lever 30 and the shaft 29. 95

The operation of my device is as follows:—

Normally the sheets of paper 21 have their slots 22 in registration with the rollers 9, 10, 13 and 15, wherefore rotatory motion of 100 the crank 37 has no effect upon moving the sheets from the device. Normally the unbalanced wheel 34, assumes the position shown in Fig. 3. Wherefore the feed roller 11 assumes its lowermost position, and when 105 the roller 11 is revolved with the shaft 12, the roller 11 exerts no pressure upon the sheets 21.

When the finger piece 32 is depressed against the yielding resistance of the spring 110

36, the feed roller or wheel 34 revolves upon its mounting, bringing the notch 35 lowermost, wherefore when the finger piece is released, the spring 36, tending to return 5 the parts to their normal positions, moves the roller 11 upwardly and exerts pressure upon the sheets.

When the crank 37 is then revolved, the action of the rollers 11 and 14 upon the 10 sheets 22, serves to carry the sheets 22 longitudinally of the device and move the slots 22 in the sheets beyond the rollers 9, 10, 13 and 15, wherefore the last mentioned rollers cooperate with rollers 11 and 14 in moving 15 the several sheets thru the device. As the feed roller 11 revolves the feed roller or wheel 34 moves therewith and upon registration of the notch 35 in the unbalanced wheel with the roller 11, the roller 11 enters 20 into the notch and can assume its lowermost position. The rollers 9, 10, 13 and 15, continue the feed of the sheets until the next 25 series of slots 22 in the sheets of paper 21, register with the rollers 13 and 15, thereby precluding further feed of the sheets.

What I claim is:—

1. In a device of the class described the combination of three shafts having their axes in substantial parallelism, rollers 30 mounted on two of the shafts adapted to cooperate in moving perforated sheets of paper between the shafts carrying said rollers, said rollers being adapted to register with slots in pieces of paper, whereby to 35 render the rollers inoperative upon the sheets of paper, another pair of rollers carried by said shafts, one of said rollers being capable of eccentric movement in relation to the shaft carrying same, and being adapted 40 to move with said shaft, and means carried by the third shaft adapted to bring the last mentioned pair of rollers into cooperative relationship upon sheets of paper, whereby to move the slots in the sheets of paper beyond the first mentioned rollers.

2. In a device of the class described the combination of a drive shaft, a driven shaft, rollers carried by the drive shaft and the driven shaft adapted to move sheets of paper 50 per therebetween and to register with slots formed in the sheets of paper, whereby to render the rollers inoperative upon the sheets, a starting roller mounted on the drive shaft and adapted to revolve therewith, the starting roller having an enlarged bore whereby relative lateral movement of said roller and the drive shaft may be attained, a roller carried by the driven shaft adapted to cooperate with the starting roller, whereby to move sheets of paper, and means to move the starting roller laterally 55 into cooperative relationship with its complementary roller on the drive shaft.

3. In a trip mechanism of the class 60 described the combination of a revoluble

roller, capable of lateral movement in relation to its axis, a roller complementary to the first roller, and from which the first roller is normally spaced, and means to bodily move the first mentioned roller toward the second roller whereby to bring the rollers into feeding relation.

4. In a trip mechanism of the class described the combination of a shaft, a roller adapted to revolve with the shaft, and capable of lateral bodily movement in relation to the axis of the shaft, a second roller adapted to cooperate with the first roller, and means to actuate the first roller bodily laterally in relation to the axis of its support 70 and to yieldingly retain said roller in cooperative relationship with the second roller.

5. In a trip mechanism of the class described the combination of a pair of normally non-cooperating feed rollers having 85 their axes normally spaced at a distance less than their combined radii, and capable of assuming a cooperative relationship, with their axes disposed at a distance substantially equal to their combined radii and 90 means to bring the feed rollers into co-operative relationship.

6. In a trip mechanism of the class described the combination of a pair of normally non-cooperating feed rollers capable 95 of assuming a cooperative relationship, and means to bring the feed rollers into cooperative relationship comprising a bearing capable of lateral movement, a stop limiting movement of the bearing in a given direction, means yieldingly resisting movement of the bearing from the stop, and a roller revolvably mounted on the bearing having a depression into which one of the feed rollers may enter, the mutilated roller 100 being weighted so as to be unbalanced when the feed roller is lodged in the depression, the mutilated roller and the yielding means being adapted to bring the feed rollers into 105 co-operating relationship when said feed roller is dislodged.

7. In a trip mechanism of the class described the combination of a pair of normally non-co-operating spaced feed rollers, one of the rollers being capable of bodily 115 movement toward the other and into cooperative relationship with the other, and means to move said laterally moving roller into co-operative relationship with the other roller.

8. In a trip mechanism of the class described the combination of a pair of normally non-cooperating spaced feed rollers, one of the rollers being capable of bodily movement toward the other and into cooperative relationship with the other, and means to move said laterally moving roller 125 into co-operative relationship with the other roller, and to automatically return the feed rollers to their normal relationship.

9. In a trip mechanism of the class described the combination of a pair of normally non-cooperating feed rollers capable of relative movement toward one another whereby to assume a co-operative feeding relationship, and means to bring the feed rollers into co-operative feeding relationship comprising a revolubly mounted roller having a depression in its periphery into which the one feed roller may extend, that portion of the roller adjacent the depression being adapted, when the feed roller is dislodged from the depression to assume a position such that the non-mutilated portion of the periphery of the roller may engage the dislodged feed roller whereby to bring the feed rollers into co-operative relationship, the dislodged feed roller being capable of returning the mutilated roller to a position such that said feed roller may again enter the depression.
10. In a trip mechanism of the class described the combination of a pair of normally non-cooperating feed rollers capable of relative movement toward one another whereby to assume a co-operative feeding relationship, means to bring the feed rollers into co-operative feeding relationship comprising a revolubly mounted roller having a depression in its periphery into which the one feed roller may extend, that portion of the roller adjacent the depression being adapted, when the feed roller is dislodged from the depression, to assume a position such that the non-mutilated portion of the periphery of the roller may engage the dislodged feed roller whereby to bring the feed rollers into co-operative relationship, the dislodged feed roller being capable of returning the mutilated roller to a position such that said feed roller may again enter the depression.
11. In a trip mechanism of the class described the combination of a pair of normally non-cooperating feed rollers capable of assuming a cooperative relationship, means to bring the feed rollers into cooperative relationship comprising a bearing capable of lateral movement, a stop limiting movement of the bearing in a given direction, means yieldingly resisting movement of the bearing from the stop, and a roller revolubly mounted on the bearing having a depression into which one of the rollers may enter, the mutilated roller being weighted so as to be unbalanced when the feed roller is lodged in the depression, the mutilated roller and the yielding means being adapted to bring the feed rollers into cooperative relationship when said feed roller is dislodged, the aforementioned yielding means being adapted to resist movement of the rollers from their normal non-cooperating relationship.

In testimony whereof, I have hereunto subscribed my name this 31st day of July, 1922.

HARRY H. KONERMAN.
